UNITED STATES PATENT OFFICE.

WILFORD HALL HORTON, OF DALLAS, TEXAS, ASSIGNOR OF ONE-HALF TO W. FRANK RUSSELL, OF DALLAS, TEXAS.

BANJO.

Application filed August 10, 1926. Serial No. 128,463.

This invention relates to improvements in banjos and more particularly to improvements in the construction of the head of such an instrument.

The ordinary head of the usual type of banjo is made of thin wood and vibrates when the instrument is played, imparting to the sound waves a harsh tone. Therefore, it is the primary object of the present invention to provide a banjo head so constructed that the sound waves which are produced through the vibration of the strings and vellum will possess their original tones and will thus be more melodious. Another object of the invention is to provide within the rim or wall of a wooden banjo head, a non-resonant lining of such thickness and of such material, over which the vellum is stretched, that the vibrations emanating from the vellum will not produce vibrations of the said rim of the head.

In the accompanying drawings:

Figure 1 is a vertical sectional view through the head of a banjo constructed in accordance with the present invention.

Figure 2 is a horizontal sectional view taken substantially on the line 2—2 of Figure 1, looking in the direction indicated by the arrows.

The banjo head embodying the invention comprises the usual rim or wall indicated by the numeral 1 and which is of wood and equipped with the usual tensioning devices 2 which coact with the usual ring 3 engaging the peripheral portion of the vellum 4 at the reinforced edge 5 thereof. The usual neck 6 is connected to the ring in the usual manner and the usual bar 7 extends diametrically of the ring in alignment with the neck. All of this structure is old and the ring 3 may be of any of the usual constructions.

The invention resides in the provision, within the rim 1, of a tone amplifying rim 8 which is of annular form and of a height somewhat greater than the height of the rim 1, so that its upper marginal portion 9 will project above the corresponding portion

of the rim 1, as best shown in Figure 1 of the drawings. The upper edge of the portion 9 is transversely rounded, as shown in the said figure, and the vellum 4 is stretched over this edge. The rim 8 is preferably of lead and it fits snugly within the wall of the rim 1 and continuously contacts the surface of the said rim, its lower margin being in registration with the lower margin of the rim. As stated, the rim 8 is preferably of lead, although any other non-resonant material possessing a sufficient degree of stiffness or rigidity may be employed for the purpose, such as some other metal or other material. Inasmuch as the rim 8 is non-resonant, there will be no vibration by the sound waves of the rim 1, as is ordinarily the case, and, therefore, the vibrations of the vellum will not be distorted and the tones will be amplified or intensified. It will be evident, therefore, that the sound waves produced in the playing of the banjo will not be distorted but will produce melodious tones.

The rim 8 will, of course, be held in place by the usual securing bolts 10 for the brackets of the tensioning devices 2, as well as by the engagement of the ends of the bar 7 through openings 11 in the rim 8 at diametrically opposite points in its circumference.

Having thus described the invention, what I claim is:

1. In a banjo, the combination with the head rim thereof, of a rim of relatively non-resonant metal fitted within the same.
2. In a banjo, the combination with the head rim thereof, of a rim of lead fitted within the same.
3. In a banjo, the combination with the head rim thereof, of a rim of relatively non-resonant metal fitted within the same and projecting at one side beyond the corresponding side of the said head rim to constitute a support over which the vellum of the banjo head is to be stretched.

In testimony whereof I affix my signature.

WILFORD HALL HORTON. [L.S.]
